CLAIM

The ornamental design for a display viewer for camera, as shown and described.

DESCRIPTION

FIG. 1 is a front perspective view of a display viewer for camera showing my new design consisting of separable first, second and third parts;

FIG. 2 is a rear perspective view of the display viewer for camera;

FIG. 3 is a right side view of the display viewer for camera;

FIG. 4 is a left side view of the display viewer for camera;

FIG. 5 is a front view of the display viewer for camera;

FIG. 6 is a rear view of the display viewer for camera;

FIG. 7 is a top view of the display viewer for camera;

FIG. 8 is a bottom view of the display viewer for camera;

FIG. 9 is a rear perspective view of a first part of the display viewer for camera of FIG. 1, shown separately to reveal aspects of the design that may not be visible in other views;

FIG. 10 is a right side view of a first part of the display viewer for camera;

FIG. 11 is a left side view of a first part of the display viewer for camera;

FIG. 12 is a front view of a first part of the display viewer for camera;

FIG. 13 is a rear view of a first part of the display viewer for camera;

FIG. 14 is a top view of a first part of the display viewer for camera;

FIG. 15 is a bottom view of a first part of the display viewer for camera;

FIG. 16 is a rear perspective view of a second part of the display viewer for camera of FIG. 1, shown separately to reveal aspects of the design that may not be visible in other views;

FIG. 17 is a right side view of a second part of the display viewer for camera;

FIG. 18 is a left side view of a second part of the display viewer for camera;

FIG. 19 is a front view of a second part of the display viewer for camera;

FIG. 20 is a rear view of a second part of the display viewer for camera;

FIG. 21 is a top view of a second part of the display viewer for camera;

FIG. 22 is a bottom view of a second part of the display viewer for camera;

(Continued)

FIG. 23 is a rear perspective view of a third part of the display viewer for camera of FIG. 1, shown separately to reveal aspects of the design that may not be visible in other views;

FIG. 24 is a right side view of a third part of the display viewer for camera;

FIG. 25 is a left side view of a third part of the display viewer for camera;

FIG. 26 is a front view of a third part of the display viewer for camera;

FIG. 27 is a rear view of a third part of the display viewer for camera;

FIG. 28 is a top view of a third part of the display viewer for camera; and,

FIG. 29 is a bottom view of a third part of the display viewer for camera.
